PROCESS FOR SULPHATING OLEFINES

Robert F. Le Baron, New York, N. Y., assignor,
by mesne assignments, to Standard Alcohol
Company, Wilmington, Del., a corporation of
Delaware

Application April 4, 1930, Serial No. 441,623

7 Claims. (Cl. 260—99.12)

The phrase "petroleum oil" as herein employed, denotes generically crude petroleum, and/or the normally liquid distillates derived therefrom. When such petroleum oil is cracked 5 to produce gasoline, a practically unbroken series of hydrocarbons is obtained ranging from hydrocarbons corresponding to the oil cracked through kerosene, gasoline and normally gaseous hydrocarbons up to and including methane. Where 10 the cracking is relatively mild as, for example, cracking carried out in liquid phase under pressures up to about 1000 pounds per square inch, the products contain olefines together with substantial proportions of paraffines. Where cracking 15 is more extensive as, for example, cracking carried out in liquid phase under pressures in excess of 400 pounds per square inch, or in vapor phase at any pressure, the proportion of paraffines is relatively less; but there is a proportionate increase in the amount of di, tertiary and higher olefines present. In either case, the 20 sulphation of the olefines presents difficulties not found in treating the pure olefines owing to the diluting influence of the paraffine hydrocarbons, and/or to a variety of chemical difficulties 25 introduced by the presence of the di, tertiary and higher olefines.

It has heretofore been proposed to sulphate the butylenes and amylenes by separating from 30 the products of cracking, a fraction the olefine content of which consists predominantly of olefines of a single number of carbon atoms corresponding to the particular olefine to be sulphated, and this procedure has to an extent minimized the difficulties, inasmuch as it permits the 35 use of a concentration of sulphuric acid which is optimum for the particular olefine to be sulphated, and eliminates from the reaction zone olefines of higher molecular weight which would 40 complicate the process both by polymerizing with each other and with the particular olefine to be sulphated. These fractions containing predominantly gaseous olefines of a single number of carbon atoms to the molecule, viz, the olefines 45 of from 2 to 4 carbon atoms both inclusive, have been treated in gas phase. I am aware that butenes have to some extent been treated in liquid phase in solution in amylenes, but the hydrocarbon fraction derived from the products of 50 cracking petroleum oil the olefine content of which consists predominantly of olefines of 4 carbon atoms to the molecule, has heretofore been treated only in gas phase. I have found that this treatment in gas phase is invariably accompanied by the loss through polymerization 55

of very substantial proportions of the particular olefine to be sulphated, and that this loss may be very substantially avoided by reacting on said such fractions in liquid phase.

The reaction in liquid phase may be carried 5 out more selectively and effectually and renders possible the successful employment of acid strengths which would be comparatively ineffective if applied to the gas phase material with a very substantial diminution in the extent to 10 which the material is polymerized. As a specific example, the fraction containing olefines of 4 carbon atoms to the molecule has heretofore been treated in gas phase with aqueous sulphuric acid of 77% or higher concentration for the sulphation of the secondary olefines contained therein. I have found that the employment of this 15 strength of acid involves the polymerization of substantial quantities and, in many cases, the major part of the secondary butene present; and that the reaction may be carried out effectively by admixing such a fraction in liquid phase with aqueous sulphuric acid of from 65 to 70 to 75%, 20 H_2SO_4 content. In particular, I find a strength of from 68 to 70 to 72% to give a highly satisfactory 25 reaction rate with relatively little polymerization and exceptional ease of control. Such a butene fraction normally contains tertiary butenes which should, for best results, be selectively removed prior to the sulphation of the 30 secondary butenes contained therein. The efficiency of the final sulphation of the secondary butenes is conditioned largely on the extent to which the tertiary butenes have been removed. In this connection, I have found that the tertiary butenes may be more cleanly and selectively separated by admixing such a fraction in liquid phase with aqueous sulphuric acid. I may employ for this purpose sulphuric acid of from 35 60 to 65%, H_2SO_4 content, at temperatures below 20° C.; but owing to the improved efficiency which I have found to be associated with the liquid phase reaction on such a fraction, I now find that I can cut the tertiary olefines cleanly and selectively without in any measurable degree polymerizing the diolefines by treating such a fraction in liquid phase with aqueous sulphuric acid of from 55 to 60%, H_2SO_4 content. Not only does this effect an improvement, per se, in the 40 efficiency of removal of the tertiaries which is shown by the superior quality and higher yield of tertiary alkyl sulphates from which the corresponding tertiary alcohols may be derived, but the subsequent sulphation of the secondary ole- 45 50 55

refrigerant is introduced by means of pipes 110 and 111 to the jacket 112 in quantity sufficient to keep the temperature of the reacting materials below 20° C. After about an hour of mixing accomplished by rotation of propeller 113, the mixture is permitted to settle. After one or two hours settling, the acid liquor consisting principally of tertiary alkyl sulphates may be withdrawn through pipe 120, controlled by valve 121, and diverted from the system through side arm 122, controlled by valve 123, to be worked up for tertiary butyl alcohol. A quantity of sulphuric acid of from 65 to 75%, H₂SO₄ content, and preferably from 68 to 72%, is then supplied to autoclave 130 and a relatively small stream of the remnant hydrocarbon material from autoclave 105 is run into autoclave 130. This is the butylene fraction after removal of tertiary olefines therefrom. The reaction in autoclave 130 is also carried out in liquid phase, and while I find it of advantage to add the olefine to the acid, this procedure may be reversed or any alternative procedure may be followed within the purview of my invention provided only that the materials are retained in liquid phase. Temperatures during this operation are preferably held between 20 and 25° C. by the introduction of a cooling medium through pipes 140 and 141 to the jacket 142. Mixing is accomplished by rotating propeller 143, and when the reaction is completed, which may require a few hours, the contents of agitator 130 are discharged through pipe 150, controlled by valve 151 to distributor 152 by which these materials are dispersed into autoclave 160. This autoclave is preliminarily charged with water for dilution of the acid products. Temperatures below 20° C. are preferably maintained during the dilution operation by introducing a cooling medium through pipes 170 and 171 to the jacket 172. At the conclusion of the dilution operation the diluted acid liquor is worked up for secondary butyl alcohol.

I will now describe the processing of the propylene fraction stored in tank 45. The autoclave 180 is preferably preliminarily charged with a quantity of sulphuric acid of from 65 to 75%, H₂SO₄ content, from 68 to 72% being preferred. A quantity of the propylene fraction is then supplied to autoclave 180 as a relatively small continuous stream by means of pipe 190, controlled by valve 191 and pump 192. During this stage, mixing is effected by rotation of propeller 182 and the temperature is preferably held below 25° C., say between 20 and 25° C., by the introduction of a cooling medium through pipes 183 and 184 to jacket 185. After completing the addition of the propylene and mixing the materials for an additional period of about one hour, the acid liquor is withdrawn through pipe 200, controlled by valve 201, and diluted in autoclave 202 to be thereafter worked up to isopropyl alcohol. The procedure for diluting the acid liquor is similar to that applied to the butylene fraction, and need not therefore be more fully described.

I will now describe the processing of the ethylene fraction held in tank 85. For this purpose, the autoclave 210 is preferably supplied with a batch of aqueous sulphuric acid of about 85%, H₂SO₄ content. A relatively small continuous stream of the ethylene fraction is then run in by means of pipe 211, controlled by valve 212 and pump 213. Mixing is accomplished during this period by rotation of propeller 214, and the temperature is held preferably between 0 and

5° C. by the introduction of a refrigerant by pipes 220 and 221 to the jacket 222. Autoclave 210 is equipped to carry the vapor pressures of ethylene in liquid phase and the reaction is carried out on the material in this condition. After conclusion of the addition of the ethylene fraction which may require several hours, the material in autoclave 210 are subjected to further mixing for a period of 3 or 4 hours and then discharged through pipe 230, controlled by valve 231 and distributor 232, into autoclave 233. Autoclave 233 is preliminarily charged with water for dilution of the acid liquor, and, inasmuch as this operation does not differ materially from the dilution of the butylene acid liquor, it will not be more fully described.

The foregoing specific description merely illustrates one specific procedure by which my invention will be carried into effect and is furnished for purposes of illustration and not by way of limitation. It is my intention that the invention be limited only by the appended claims or their equivalents in which I have endeavored to claim broadly all inherent novelty.

I claim:

1. Process of sulphating secondary butene contained in a mixture of hydrocarbons produced by cracking petroleum oil, which comprises separating from said mixture by distillation a fraction, the olefine content of which consists predominantly of a mixture of branched and straight chain olefines having four carbon atoms to the molecule, and admixing said fraction in liquid phase with aqueous sulphuric acid of from 50-60% H₂SO₄ content, removing the aqueous acid layer and admixing the residual hydrocarbons in liquid phase with aqueous sulphuric acid of from 65 to 70%, H₂SO₄ content.

2. Process of sulphating secondary butene contained in a mixture of hydrocarbons produced by cracking petroleum oil, which comprises separating from said mixture by distillation a fraction, the olefine content of which consists predominantly of secondary and tertiary olefines of four carbon atoms to the molecule, selectively removing tertiary olefines from said fraction by contacting with aqueous sulphuric acid of from 50-60% H₂SO₄ content, removing the aqueous acid layer with the tertiary olefines in solution, and thereafter sulphating the secondary olefines contained in said fraction by admixing said fraction in liquid phase with aqueous sulphuric acid of from 65 to 70%, H₂SO₄ content.

3. Process of sulphating secondary butene contained in a mixture of hydrocarbons produced by cracking petroleum oil and containing both secondary and tertiary olefines of four carbon atoms to the molecule, which comprises separating from said mixture by distillation a fraction, the olefine content of which consists predominantly of secondary and tertiary olefines of four carbon atoms to the molecule, selectively removing tertiary olefines from said fraction by admixing said fraction in liquid phase with 55 to 60% sulphuric acid, and thereafter sulphating the secondary olefines contained in said fraction by admixing said fraction in liquid phase with aqueous sulphuric acid.

4. Process according to claim 3, in which the selective removal of tertiary olefines is accomplished by admixing said fraction in liquid phase with sulphuric acid of from 55 to 60%, H₂SO₄ content, at temperatures not exceeding 20° C.

5. Process of sulphating secondary butene contained in a mixture of hydrocarbons produced by

cracking petroleum oil and containing both secondary and tertiary olefines, which comprises separating from said mixture by distillation a fraction, the olefine content of which consists predominantly of secondary and tertiary olefines of four carbon atoms to the molecule, selectively removing tertiary olefines from said fraction by admixing said fraction in liquid phase with aqueous sulphuric acid, and thereafter sulphating the secondary olefines contained in said fraction by admixing said fraction in liquid phase with aqueous sulphuric acid of from 65 to 70%, H₂SO₄ content.

6. Process according to claim 5, in which the selective removal of tertiary olefines is accomplished by admixing said fraction in liquid phase with aqueous sulphuric acid of from 55 to 60%, H₂SO₄ content.

7. Process according to claim 5, in which the selective removal of tertiary olefines is accomplished by admixing said fraction in liquid phase with aqueous sulphuric acid of from 55 to 60%, H₂SO₄ content, at temperatures not exceeding 10 20° C.
